Myself

UNITED STATES PATENT OFFICE.

JAMES M. CALHOUN, OF PLYMOUTH, PENNSYLVANIA.

WATCH-BOW FASTENING.

SPECIFICATION forming part of Letters Patent No. 415,996, dated November 26, 1889.

Application filed August 19, 1889. Serial No. 321,273. (No model.)

To all whom it may concern:

Be it known that I, JAMES M. CALHOUN, a citizen of the United States of America, residing at Plymouth, in the county of Luzerne 5 and State of Pennsylvania, have invented certain new and useful Improvements in Fastening Pendent Bows for Stem-Winding-Watch Cases, of which the following is a specification, reference being had therein to the accompanying drawings.

My invention pertains to an improvement in pendent watch-bows for stem-winding watches; and it consists in the novel construction, combination, and arrangement of parts, 15 substantially as hereinafter more fully shown and described.

In the accompanying drawings, Figure 1 is a vertical section of my invention. Fig. 2 is a plan view of one of the fastenings. Fig. 3 20 is an enlarged detail view in section of one side of the bow.

In constructing my watch-bows for stem-winding watches I employ watch-stem A, having integral therewith right-angular arms a 25 a, provided with sockets b b, for reception of stemmed cones D. The ends of the bows B are apertured for reception of the stems B' of cones D, the cones being tapered and lengthened from their vertex to form the stems 30 shown. The stems B' project through ori-

fices formed at either end of bows B, and their ends are riveted and fitted flush with the periphery of the bows. The stemmed cones D are first inserted in sockets b, and then metallic sleeve c is fitted into stem A, 35 which completes the work, sleeve c fitting flush against the inner periphery of the stem. As thus shown, an inexpensive and highly-efficient watch-bow for stem-winding watches is constructed.

Having thus fully described my invention, what I claim, and desire to secure by Letters Patent, is—

1. A watch-bow for stem-winding watches, consisting of a stem having socketed right-angular arms for reception of stemmed cones for securing the bow ends, the cones being secured by a sleeve inserted in the stem, substantially as shown and described. 45

2. In a watch-bow for stem-winding watches, 50 the combination of the stem having arms, the stemmed cones, and the sleeve for securing the bow ends, substantially as shown, and for the purpose described.

In testimony whereof I affix my signature in 55 presence of two witnesses.

JAMES M. CALHOUN.
